178,867

MOBILE SELF-POWERED ENGINE STARTER FOR JET AIRCRAFT

Daniel B. Coleman, Los Angeles, Calif., assignor to
North American Aviation, Inc.

Application March 3, 1955, Serial No. 34,855

Term of patent 14 years

(Cl. D14—3)

FIG. 1

Des. 178,867

PAGE 2

FIG. 2

FIG. 3

FIG. 4

FIG. 5

Fig. 1 is a top plan view of a mobile self-powered engine starter for jet aircraft showing my new design.

Fig. 2 is a side elevational view of the left hand side of the starter as shown in Fig. 1.

Fig. 3 is a side elevational view of the right hand side of the starter as shown in Fig. 1.

Fig. 4 is a front elevational view of the starter, taken from the left as shown in Fig. 2.

Fig. 5 is a rear elevational view of the starter, taken from the right as shown in Fig. 2.

The dominant features of my design reside in those portions shown in full lines.

I claim:

The ornamental design for a mobile self-powered engine starter for jet aircraft, substantially as shown and described.
